UNITED STATES PATENT OFFICE.

DAVID LARSON, OF YONKERS, NEW YORK, ASSIGNOR TO OTIS ELEVATOR COMPANY,
OF JERSEY CITY, NEW JERSEY, A CORPORATION OF NEW JERSEY.

CONTROLLING MECHANISM.

1,016,834.

Specification of Letters Patent. Patented Feb. 6, 1912.

Application filed July 18, 1911. Serial No. 639,081.

To all whom it may concern:

Be it known that I, DAVID LARSON, a subject of the King of Sweden, residing at Yonkers, in the county of Westchester and 5 State of New York, have invented a new and useful Improvement in Controlling Mechanism, of which the following is a specification.

My invention relates to a system of control for electric motors, more particularly to 10 the control of motors for elevator or other hoisting apparatus.

One object of my invention is to prevent the motor from either attaining an unsafe 15 speed or running at too slow a speed.

A further object is to prevent a reverse current in the motor field when the motor is driven by the load.

Other objects of the invention and the 20 exact nature thereof will appear hereinafter.

A compound wound motor for hoisting apparatus possesses the features of heavy starting torque, and constant speed when the shunt field alone is excited. It is the 25 usual practice to excite both fields in starting and to short-circuit the series field after the motor is accelerated. When the load drives the motor as a generator a reverse current will flow in the series field windings, 30 which tends to weaken the total field strength, and this may, under certain conditions, reach a dangerous limit.

My invention relates particularly to the control of the series field.

35 In the accompanying drawings, Figure 1 is a top or plan view of an accelerating magnet constructed in accordance with the principles of my invention; Fig. 2 is an end elevation view of the same; and Fig. 3 is a 40 wiring diagram showing circuit connections for an elevator installation utilizing my system of control.

Referring more particularly to Figs. 1 and 2, the accelerating magnet comprises a 45 magnet winding 10 secured to a magnet frame 11 which is fastened to a switchboard or support 12 and provides also a core 13 for the magnet winding. On this magnet frame 11 contact arms 14 are mounted by 50 the pivot 15 and are arranged to be drawn up to the magnet core 13 in accordance with the energization of the magnet. These contact arms 14 are formed with enlarged portions or weights 14' so disposed as to cause

the arm to fall back when the magnet is not 55 energized, adjustable stops 16 being located on the magnet frame 11 to limit the backward movement of each arm. At the contact ends of the arms 14 are contacts 1, 2, 3, 4 and 5 each insulated from its carrying 60 arm and having a terminal connection 18 for an electrical conductor. A contact holder 21 secured to the support 12 and comprising contact holding members clamped together by screws 23, or other fastening devices is 65 adapted to hold stationary contacts 20 opposite the movable contacts 1, 2, 3 and 4. A projection 24 of the contact holder 21 supports a contact 25. A contact 26 for making connection with the contact 25, is 70 held by a movable yoke-shaped member 27 formed on the upper end of an arm 28 pivoted on the rod 15. This member 27 also holds a contact 20' in position to make connection with the contact 5, the form of the 75 said member and the disposition of the contacts being such that only one pair of contacts 25 and 26, or 20' and 5, are together at a time. When the accelerating magnet is de-energized, a coil spring 31, interposed be- 80 tween the yoke 27 and the stationary arm 24, holds said yoke in its forward position with the contacts 25 and 26 in engagement.

When the magnet winding 10 is energized with a gradually increasing current the contact arms are drawn up in succession, the one opposite the contact 20' being the last one to be so drawn up. When connection is made with contact 20' the member 27 is thrust back separating contacts 25 and 26. It is 85 to be understood that the successive operation of the contact arms is regulated by the adjustment of the stops 16. Both the holder 21 and the supporter 27 are electrical conductors. 95

An embodiment of my invention diagrammatically shown by Fig. 3, will now be explained. In this figure a car C and counterweight W are shown connected to a driving motor M. The motor receives current from 100 the mains and through a main switch S and one of the reversing switches R and R', the reversing switches being controlled by the switch K in the elevator car C. An electro-responsive brake B and the shunt field F are 105 connected through auxiliary contacts r of either reversing switch to the mains. The accelerating magnet A with its magnet coil

10 connected through the auxiliary contacts *r* of either reversing switch across the armature of the motor *M* controls the starting resistance *X* and with the aid of the device 5 *D* controls the series field *E*. As soon as a reversing switch is closed, the shunt field *F* and brake winding 34 are connected across the mains, the magnet winding 10 is connected across the motor armature and 10 the motor armature receives current from the mains through the series field *E* and the starting resistance *X*. This circuit through the armature is traced from the negative lead 35, by way of conductor 36, series field 25 *E*, conductor 37, starting resistance *X*, conductors 38, 39, through a reversing switch contact, the motor armature, and another reversing switch contact to the positive lead 40. The motor starts with all the armature 20 resistance *X* and the series field *E* in series with the armature, and as the motor speeds up, the accelerating magnet winding 10 which is connected across the motor armature has the counter-electro-motive force of 25 the motor applied to it and the accelerating magnet contacts 1, 2, 3, 4 and 5 are drawn up in regular succession, thereby short-circuiting portions of the sectional resistance. The terminals of the series field *E* are connected to the contacts 4 and 5, and as soon as the contact 5 is drawn up to contact 20' the series field and the starting resistance are short-circuited by way of the member 27 connected to the conductor 39. When the 35 contacts 5 and 20' are joined, the contacts 25 and 26 are separated, the attractive force of the accelerating magnet for the contact 5 being sufficient to overcome the tension of the spring 31. Although a path may be 40 traced from contact 5 through the series field *E*, contact 4, contact holder 21, contact 1, and a portion of the starting resistance *X* to the conductor 39, and parallel with the path through the member 27 from conductor 45 to 35 to conductor 39, the resistance of the first-named path is so great in comparison to the latter that no appreciable current flows through the series field. The resistance of a series field alone is so small that 50 it is frequently found in practice that the resistance of the contacts in a parallel circuit are equal to or greater than the resistance of the series field.

It is evident that the path through the 55 member 27 may be of the smallest resistance, for there is only one contact connection to be made and in comparison with the two contact connections and the portion of starting resistance in series with the series field, 60 constitutes substantially a short-circuit around the series field. This connection, however, does not sever the series field connections, and there can be no danger of an open armature circuit by reason of the failure 65 of the device *D* to operate. When the

series field is short-circuited the motor operates at constant speed as a simple shunt motor.

If the motor is being driven by a load the accelerating device will be energized when a certain speed is attained, and the device *D* operates to short-circuit the series field thus preventing the series field from weakening the magnetism set up by the shunt field. 75

The operation is entirely automatic and does not depend upon the skill or discretion of the attendant.

The device may easily be adapted to apparatus already in operation, is simple in construction, and is effective, efficient and reliable. 80

I desire not to be limited to the precise construction and application of the invention as herein set forth, for it is evident that those skilled in the art to which this invention appertains may make various changes without departing from the spirit and scope thereof. 85

What I claim is:—

1. In a system of motor control, the combination with a compound wound electric motor, of starting resistance therefor, and a device controlled by the motor for short-circuiting said starting resistance and for closing a short-circuit around the resistance and the series field winding of the motor and introducing resistance in series with the said field winding. 90

2. In a system of motor control, the combination with a compound wound electric motor, of a sectional starting resistance therefor, and means dependent upon the speed of the motor to short-circuit sections of the said resistance and to close a short-circuit around the resistance and the series field winding of the motor and introduce resistance in series with the said field winding. 100

3. In a system of motor control, the combination with a compound wound electric motor, of a sectional starting resistance in series with a field winding of the motor, and means controlled by the motor to close short-circuits across sections of the starting resistance, to close a short-circuit around the resistance and the series field winding of the motor, and to again open one or more of said first-named short circuits. 110

4. In a system of motor control, the combination with a compound wound electric motor, of sectional starting resistance, and an electro-magnet controlled by the motor to short-circuit sections of the starting resistance, to close a circuit around the starting resistance and the series field winding of the motor, and to remove the said short circuit. 125

5. In a system of motor control, the combination with a compound wound electric motor, of sectional starting resistance in 130

series with the series field winding of the motor, and an accelerating magnet operative to short-circuit sections of the starting resistance, to close a short-circuit around the starting resistance and the series field winding of the motor, and to again introduce a portion of the starting resistance in circuit with the series field winding.

6. The combination with a compound wound electric motor, of sectional starting resistance therefor in circuit with the series field winding of the motor, and an accelerating magnet dependent for energization upon the counter-electro-motive force of the motor and operative to short-circuit sections of the starting resistance, to close a short-circuit around the starting resistance and the series field winding of the motor, and to again open the first-named said short-circuit around the starting resistance.

7. The combination with a compound wound electric motor, of sectional starting resistance therefor, an accelerating magnet connected across the motor armature with contacts arranged to be attracted in succession, the two contacts last attracted being connected to the terminals of the series field winding, and a movable contact member with which the last accelerating magnet contact connects and which is operative to short-circuit the series field and the starting resistance through a path containing only one contact connection.

8. The combination with a compound wound electric motor, of sectional starting resistance therefor, an accelerating magnet controlled by the motor with movable contact arms and contacts arranged to short-circuit portions of the starting resistance, two contacts being connected to the terminals of the series field, a movable contact member to complete a connection for short-circuiting the said portions of the starting resistance and operative when a predetermined contact arm is moved to break the said connection and to complete a short-circuit connection around the starting resistance and the series field.

9. The combination with a compound wound electric motor, of sectional starting resistance therefor, an accelerating magnet

dependent for energization upon the speed of the motor and having movable contact arms with contacts arranged to short-circuit portions of the starting resistance, the two contacts last moved being connected to the terminals of the series field, a fixed contact member with which the movable contacts make connection, a spring-pressed contact member to make connection with this fixed contact member having also a contact to make connection with the contact on the contact arm last moved and moved by the said arm against the spring pressure to break the said connections and to establish with the said contact a short-circuit around the entire starting resistance and the series field.

10. The combination of an accelerating magnet, a sectional resistance, an electro-responsive device in circuit with said resistance, means operated by said magnet for short-circuiting the sectional resistance, and means operated by the magnet to open the short circuit through said resistance and close an additional circuit in shunt to the resistance and said electro-responsive device.

11. The combination of an electric motor comprising a series winding, a resistance in circuit with said winding, an accelerating magnet, and means controlled and operated by said magnet for short-circuiting said resistance, closing a circuit in shunt to said winding, and then opening said short-circuit.

12. The combination of an electric motor,—comprising a series winding, resistance in the circuit of said winding, means for reducing the resistance of said circuit, establishing a low resistance circuit in shunt to said winding, and then increasing the resistance of the said series winding circuit when said low resistance circuit is established.

In testimony whereof, I have signed my name to this specification in the presence of two subscribing witnesses.

DAVID LARSON.
